BOAT DAVIT

Klaus L. Cappel, San Francisco, Calif.

Application January 30, 1948, Serial No. 5,369

8 Claims. (Cl. 9—38)

1

Existing types of davits, and more particularly those of the gravity type, suffer from a number of disadvantages. For one thing, their component parts are not integrally connected together, but perform translatory movements with respect to each other. This, on the one hand, makes them less stable when being shaken by the rolling of the ship among waves, while on the other hand it is the cause of considerable frictional resistance. Furthermore, the forces applied to these davits in order to hoist them from an outboard to an inboard position are mostly unfavorably disposed, so that a large amount of power is unnecessarily required to accomplish this end. Their working parts are not readily accessible, thus creating maintenance problems. Their structure is considerably jarred by the abrupt termination of the launching movement.

Life boat davits operated by gravity are nevertheless favorite devices for launching boats in emergencies. They require a minimum of human interference beyond the first simple release of boat lashings. Their action is not affected by failure of electrical power or destruction of machinery, such as are likely to occur in a disaster at sea, and their operation does not depend on the concerted manual effort of a number of men apt to act confusedly under the threat of loss of life.

To the requirement of simple and automatic operation, certain other important practical elements must be added. Since a sinking vessel usually departs from its normal upright position, the mechanical features of a davit should be such as to enable it to work even under adverse conditions of list and trim of the ship. Also, tilting of the supporting deck should not shift any parts of the mechanism relative to each other, creating new points of contact and thus increasing frictional resistance.

The effectiveness of a conventional type gravity davit may be impaired by yet another condition. Each of the pair of davit arms required to handle a boat is controlled by a long line or rope, and in course of time these lines will stretch. If their lengths increase by unequal amounts, and such a change goes unnoticed and uncorrected, then, upon lowering the boat, one davit arm will be somewhat ahead of, and lower than, the other, and the distance between both davit heads will be increased. Since the boat suspended from these davit heads acts as a spacer tending to keep their distance constant, the davit heads will be pulled towards each other, and the davit arms be brought to bear lat-

2

erally against their respective supports, with a force that increases as the phase difference between the davits grows with the inequality of their respective lines. If the difference in stretch has reached a critical limit, such force may be sufficient, on lowering the boat, to jam the davit arm which is "behind," since it carries the lesser weight. The davit arm which is "ahead" may carry a sufficiently great overload to overcome the friction at its base, caused by the pull of the attached boat, and thus will continue to swing out alone, in which process it tears the boat from the other, jammed davit arm, upsets it and frequently smashes it against the side of the ship. A well-constructed davit should therefore remain unaffected in its capacity to swing out, in spite of a more than inconsiderable phase difference of its two component units.

By their nature, life boats and their davits must be carried on open decks, where they are subject to the deteriorating influence of salt spray and rain. To prevent possible failure of the davit from slow destruction, its working or contacting surfaces should be kept to a minimum, and be protected from the weather. Moreover, since maintenance operations on shipboard are not likely to be too thorough, these working surfaces (such as pins, bearings, tracks, etc.) must be readily accessible, and must be capable of being serviced even by inexperienced hands, without endangering the efficiency of the apparatus.

Owing to the constant rolling of a ship among waves, all its structures, and especially those on the upper decks, are subject to considerable stresses. A life boat davit must be designed to withstand deformation which, if carried far enough, would render its working parts ineffective, to the danger of all aboard.

These requirements pose a problem which is extremely difficult of solution, even with compromises of ideally necessary requirements. In the invention here explained, I have provided a davit in which the above-mentioned potential sources of failure have been largely eliminated.

My invention relates to boat davits of the type in which gravity is depended on for moving the suspended and supported lifeboat from an inboard position of stowage in the davit arm to an outboard or launching position.

One object of my invention is to obtain smoothness of the launching operation through employment of exclusively rotatory movements in the davit mechanism.

Another object is the increase in safety of the launching process through provision of great-

er lateral stability of the davit arm, thus avoiding deformation of the davit structure and consequent jamming.

Another object is the avoidance of the one or several abruptly terminated stages into which the swinging-out process is divided in prior art davits of this general type, and the substitution of a single, smooth, self-limiting movement, with a resulting avoidance of sudden stresses in the structure.

Other objects include operation of the davit even under adverse conditions of list and trim of the ship, and reduction of maintenance requirements, with a resulting decrease in the effect of deterioration and neglect on the reliability of the davit.

The invention possesses other objects and features of value, some of which, with the foregoing, will be set forth in the following description of the invention. It is to be understood that I do not limit myself to this disclosure of species of my invention, as I may adopt variant embodiments thereof within the scope of the claims.

Referring to the drawings:

Figure 1 is a side view of a preferred embodiment of my davit, supported by the ship's deck, with the stowed boat seen in front elevation;

Figure 2 is a front view of the davit of Figure 1;

Figure 3 is the same side view as Figure 1, but with the davit arm swung out to its furthest outboard position, and the boat released from the davit head;

Figure 4 is a skeleton diagram of the davit mechanism, showing the schematic arrangement and movement of its component parts;

Figure 5 is a modification of the embodiment of Figure 1, showing the davit supported at its inboard end by a deck house, thus leaving the deck underneath free for passage;

Figure 6 shows a method of obtaining the phantom pivot center about which the davit turns, in terms of coordinate geometry.

The principle underlying my davit is illustrated schematically in Figure 4, which shows essentially a simple four-bar linkage. To a fixed bar 2 are attached links 3 and 4 by pivotally mounting them on pins 5 and 6, respectively, to permit rotational movement thereof. A connecting link 7 is pivoted to the free ends of the links 3 and 4 by pins 8 and 9, respectively. The connecting link 7 at an intermediate point carries a rigidly attached arm 12 upwardly directed, to whose upper end a pulley 13 is journaled by a pin 14. A line from the pin 14 to the point of attachment of the arm 12 to the link 7 makes an angle 16 of less than 90 degrees with such link 7, while a line from said pin 14 to the pivot pin 8 makes an angle 17 of about 15 degrees with the vertical.

Near its upper end, the arm 12 is provided with a lateral forked extension 18, which carries a weight 19 which corresponds to the weight imposed on the davit by a lifeboat which acts on the mechanism in a downward direction. A rope 20 is attached to the weight 19, and passes over the pulley 13 in the direction of the pulley 15, thus producing a resulting force on the upper end of the arm approximately in the direction 21.

The links 3 and 4 are capable of rotating about the pins 5 and 6 respectively, in circular paths 22 and 23, respectively. The connecting link 7, and thus the arm 12 and all parts rigidly attached to it, can be shown to rotate, with respect to the fixed bar 2, about a constantly shifting phantom pivot center which travels along the curve 24. Any point on the curve 24 is determined by

the intersections of the longitudinal axes of the links 3 and 4. Thus, when the pins 8 and 9 have travelled along the paths 22 and 23 to some such points as 26 and 27 respectively, the pin 14, at 5 the upper end of the arm 12, will have moved along the path 28 to position 29, at which stage the instantaneous phantom pivot center will be at the point 30 on the path 24. This represents a typical intermediate position of the assembly.

When the links 3 and 4 have reached their end positions, approximately at 31 and 32 respectively, the pin 14 will be at the point 33.

It can be readily seen from Figure 4 that the force of the weight 19, acting downwardly under the pull of gravity, in directions 25, 25a, 25b, is always on the "outboard" side of the instantaneous phantom pivot center about which the link 7 and attached arm 12 are rotating, so that a constant restraining force must be exerted to 10 balance it, as by means of the rope 20. It may also be seen from a comparison of the paths of travel 24 and 28, that for the greater part of the movement of the links 3, 4 and 7, the horizontal component of the displacement of the phantom 15 pivot center is less than the horizontal component of travel of the pin 14. It is not until the links 3 and 4 approach a parallel direction, such as 20 are shown on Figure 4, that a more rapid displacement of the instantaneous phantom pivot 25 center takes place.

Since the only external forces acting on the mechanism are those exerted by the suspended weight 19 and the rope 20, the laws of statics demand that the resultant 21 always passes 30 through the instantaneous phantom pivot center. As the pin 14, and with it the point of application of the resultant 21b, approach the "outboard" position 33, both the direction and the point of displacement of the resultant change by 35 increasingly smaller increments, while the displacement of the instantaneous phantom pivot center is greatly accelerated. If motion were to 40 continue, the phantom center would soon be located on the outboard side of the resultant 21b, which is statically impossible. The mechanism will therefore come to an automatic stop, as a 45 result of the "converging" tendency of the resultant 21b and the instant center, without any material stops being required.

At this point, the weight 19, having travelled 50 along a path 28a, slips out of the forked extension 18 when the latter has been tipped downwardly by rotation of the arm 12, and further paying out of the rope 20 allows it to descend 55 vertically, without further movement of the mechanism.

An additional feature of the mechanism is a 60 peculiar self-damping or braking action, which again may be explained with reference to the instantaneous phantom pivot center. If the mechanism is allowed to move toward the "outboard" position by rapidly paying out the rope 20, it may "overshoot the mark" i. e. reach a 65 position in which the resultant 21b passes to the "inboard" side of the instantaneous phantom pivot center, owing to the inertia of the system. When the resultant inboard turning moment has become large enough to overcome the dynamic outboard turning moment, the arm 12 will turn 70 inboard again, and after a few oscillations adopt the final "outboard" equilibrium position required by statics.

In summary, it may be affirmed that the most 75 essential and characteristic feature of this mechanism is the behavior of its instantaneous phan-

tom pivot center with respect to the point of suspension of the weight 19, and that if this behavior is known, all other features can either be derived from it or made to fit it for the best possible effect. A general expression describing every phase of these relative movements explained above may therefore truly be said to embody the chief characteristic of the invention, and such an expression can be set up in terms of descriptive geometry.

In Figure 6, the mechanism of Figure 4 is shown arranged in a coordinate system, with the X-axis passing through the fixed pins 5 and 6, and the Y-axis passing through one of these pins, say the pin 5, at right angles to the X-axis, so that the origin of the system is at the pin 5. It can easily be shown that for any position of the mechanism, the location (x, y) of the instantaneous phantom pivot center, and the corresponding location (x', y') of the pin 14 in this coordinate system are given by the equations:

$$x = \frac{K}{1 - \frac{\tan \alpha}{\tan \beta}}$$

$$y = X \tan \alpha$$

$$x' = \frac{K + \cos \alpha + M \cos \beta}{2} + R \cos(\gamma + \delta)$$

$$y' = \frac{\sin \alpha + M \sin \beta}{2} + R \sin(\gamma + \delta)$$

$$\gamma = \arcsin \left(\frac{M \sin \beta - \sin \alpha}{L} \right)$$

$$\beta = \arccos \left(\frac{K^2 + M^2 + 1 - 2K \cos \alpha - L^2}{2M\sqrt{K^2 + 1 - 2K \cos \alpha}} \right) \mp$$

$$\arccos \left(\frac{K - \cos \alpha}{\sqrt{K^2 + 1 - 2K \cos \alpha}} \right)$$

where x , y , x' and y' are measured in multiples of the link at the origin, which link is taken as unity,

"K" is the distance between the pins 5 and 6, expressed in multiples of the link at the origin,

"L" is the length of the link 7, between pins 8 and 9, expressed in multiples of the link at the origin,

"M" is the length of the link 4 expressed in multiples of the link at the origin,

" α " is the angle made with the X-axis by the link at the origin,

" β " is the angle made with the X-axis by the other link, in this case the link 4,

"R" is the distance between the pin 14 and the midpoint of the length "L" of the link 7, expressed in multiples of the link at the origin,

" γ " is the angle made with the length "L" by the length "R,"

" γ " is the angle made with the X-axis by the length "L," i. e. the link 7.

All the characteristic features of the mechanism which have been described above, are concisely and exactly expressed in the above equations, and the curves 36 and 37 may easily be derived from them. But in addition, these equations also furnish a theoretical basis for a simple method of designing the elements of the mechanism, such that any desired range of travel of the pin 14 can be obtained.

The critical part of the curve 24 of instantaneous phantom pivot centers, as shown on Figure 4, lies above the X-axis, where the rate of travel of the phantom center is accelerated,

which has been shown above to be the cause of both the self-stopping and the self-damping action of the mechanism. This acceleration occurs when the links 3 and 4 approach a parallel orientation, i. e. when the angles α and β , Figure 6, are equal, and the curve 24 approaches an asymptote cutting the X-axis about half-way between the pins 5 and 6, and making an angle α_{as} with such X-axis equal to both α and β , and ex-

10 pressed by

$$\alpha_{as} = \arccos \left(\frac{K^2 + (M+1)^2 - L^2}{2K \cdot (M+1)} \right)$$

A large value of α_{as} thus means a steep curve 15 24 above the X-axis, and a small value of α_{as} indicates a curve 24 with little slope in that region. But since the angle α_{as} is also approximately equal to half the angle through which the links 3 and 4 turn in their passage from one 20 limiting position to another, it will be readily seen that the angle α_{as} also gives an approximate indication of the range of travel of the pin 14, which is thus dependent on the relationships between the lengths K, L, M and R.

25 However, an additional important consideration enters into the choice of proportions of these lengths. The automatic action of the mechanism under the influence of gravity depends on the existence, at all times, of a large moment arm 30 of the weight 19 about the instantaneous phantom pivot center. Now it can be shown that when the angle α_{as} is large, the curve 24 of phantom pivot centers billows out laterally below the X-axis to such an extent that the moment arm is greatly diminished or even vanishes 35 for large values of α_{as} , so that the mechanism, in spite of having a large range of travel, would be halted in an intermediary position and would never reach its intended final position under the influence of gravity alone.

In proportioning the mechanism, it is therefore necessary to compromise between a large range and a perpetually large moment arm, and this is achieved by making the inclination angle 45 α_{as} of the asymptote an intermediate value, neither too large nor too small. Making use of the equations given above, and bearing in mind the relationships of the various elements, it then becomes a simple matter to design a mechanism 50 which will automatically travel in a predetermined range.

In actual practice, it will be found that for the most favorable locus or curve of instantaneous phantom pivot centers, the link 7, Figure 4, 55 should be no larger than the distance between the fixed pivot pins 5 and 6, and the additive lengths of the rotating links 3 and 4 should be less than the distance between their points of attachment to the fixed bar 2, by the pins 5 and 60 6, i. e.

$$L = K, 1 + M < K$$

It will be readily seen that the mechanism described above can be advantageously embodied in 65 a gravity davit, as it achieves by means of a few simple elements, suitably arranged, automatic movement within a finite, self-determined range. Bearing in mind the kinematic relationships discussed above, any desired travel of the extremity of the arm 12 may be obtained by proper proportioning and spacing of the various elements, and thus the resulting gravity davit may be made to fit any shape and size of boat. The physical features of such a davit are described below, in connection with Figures 1, 2, 3 and 5.

Securely fixed to the deck 39 of a vessel are the two units of the davit structure, spaced apart a distance somewhat less than the length of the boat 41 which the complete 2-unit davit is to carry. Each unit includes a frame 40 comprising a pair of parallel spaced plates. Pivoted between these plates as by the pins 42 and 43 are the links 44 and 45, whose free ends are cut out or forked to accommodate the davit arm 46, as shown on Figure 2. The davit arm broadens at the base, as shown on Figure 1, the ends of the base being provided with journals 47 and 48, which in turn are pivoted to the free ends of the links 44 and 45 by pins 49 and 51 respectively.

The davit arm is arched or otherwise shaped to accommodate the hull of a boat 41, as shown on Figure 1. The keel 52 of the boat is supported in the stowed position of the boat by a keel chock 53, while the side of the boat rests against the gunwale chock 54, both chocks being arranged on the arm 46 as shown on the drawings.

Means are provided for controlling the movement of the davit arm, and for dropping the boat into the water from its final position, Figure 3. To the releasing gear 56 in each end of the boat 41, a T-shaped hanger 57 is attached. A fall 58, attached to the top of the T-hanger, passes over a sheave 59 journaled in the davit head, over another sheave 61 journaled in the davit arm somewhat lower down, around fixed sheaves 62 and 63 journaled in the davit frame 40, around a deck sheave 64, and thence to one side of a dual windlass drum. A similar fall 66 is rovèn through the sheaves of the davit arm and frame in the other unit of the davit arrangement, and after passing around the deck sheave 67 runs to the other side of the dual windlass drum. The windlass is a conventional feature of all similar types of davit arrangements and is therefore neither shown on the drawings nor described in the text.

Extending from both sides of the davit head are a pair of sturdy cheek plates 68, whose lower parts are fashioned into hooks 69, into which fits the crossbar of the T-hanger 57, as shown on Figure 2. As shown on Figure 3, movement outboard and downwardly of the davit arm, tips the hooks downwardly to allow the T-bar to slide off as the davit reaches its inclined position, at which time the falls 58 and 66 assume the weight of the suspended boat which may then be lowered by paying out the falls from the windlass. Raising the boat to engage the T-hanger 57 against the edges of the cheek plates 68 leaves the crossbar in position to be caught by the hooks 69 when the davit arm is swung back to its upright position. The hooks 69 may also be made of one piece and attached to the underside of the davit head, or be otherwise integrally connected with it. In any case, they are a standard feature of all gravity davits and are not claimed as original, being indispensable to other types as well.

In order to avoid the strain which would be placed upon the ends of the boat if it were left suspended in the stowed position, the length of the hanger 57 is adjusted, by means of a short chain, 71, or by other means, so that the keel chock 53 will engage the keel 52 of the boat from underneath during the last part of the stowing operation, and will continue to support it in the stowed position, thus also relieving the strain on the hooks 69.

The inboard edge of the davit arm 46 may be locked in the stowed position against the frame

40 by means of any known reliable quick-release device, not shown on the drawings.

The choice of dimensions of the various structural parts will depend in part on the size of the boat which the davit is to handle. The extent of the lateral travel of the davit head is governed by the width of the boat, plus the required distance it is to be held away from the side of the ship during launching. These conditions give the approximate length of the davit arm 46, and also the locations of its two end positions.

Furthermore, the shipping authorities demand that a life boat davit be still operative at a certain specific adverse list of the vessel. Therefore, the proportions of the various parts must be so adjusted that the suspended boat will always exert a sufficiently large outboard turning moment upon the arms in these adverse conditions. Keeping in mind the interaction of the various parts, it is possible to fulfill all the requirements enumerated above by means of the davit mechanism here described.

While I have described my invention in its preferred form and in considerable detail, the same is subject to alteration and modification without departing from the underlying principles involved, and I accordingly do not desire to be limited in my protection to the specific details illustrated and described herein except as may be necessitated by the appended claims.

I claim:

1. A gravity type davit unit for launching a boat from the deck of a ship, comprising a frame for mounting on such ship, a pair of pivot pins mounted in parallel relationship on said frame, a pair of links, each rotatably mounted on one of said pins, a davit arm for carrying a boat, means pivotally securing said davit arm at one end to said links, with its boat suspending end at all times outboard of the instantaneous point of intersection of the longitudinal axes of said links, said pair of links constituting the only means of connection between said arm and said frame, and the additive lengths of said pair of links being less than the distance between their points of attachment to said frame, and means for removably suspending a boat from said arm in the inboard position thereof.

2. A gravity type davit unit for launching a boat from the deck of a ship, comprising a frame for mounting in fixed position on such ship, a pair of pivot pins mounted in parallel relationship on said frame, a pair of links, each rotatably mounted on one of said pins, a davit arm for carrying a boat, means pivotally securing said davit arm at one end to said links, with its boat suspending end at all times outboard of the instantaneous point of intersection of the longitudinal axes of said links, said pair of links constituting the only means of connection between said arm and said frame, and the additive lengths of said pair of links being less than the distance between their points of attachment to said frame, a pulley mounted in fixed position adjacent the other end of said arm, means for removably suspending a boat from said arm in the inboard position thereof, and a fall running over said pulley and attached to said removable suspension means.

3. A gravity type davit unit for launching a boat from the deck of a ship, comprising a rigid frame for mounting in fixed position on such ship, said frame involving a pair of parallel spaced plates, a pair of pivot pins mounted in parallel relationship transverse of said frame, a pair of links, each rotatably mounted on one of

said pins, a davit arm for carrying a boat said davit arm having a broadened base, means pivotally securing said davit arm at said base to said pair of links, with its boat suspending end at all times outboard of the instantaneous point of intersection of the longitudinal axes of said links, said pair of links constituting the only means of connection between said arm and said frame, and the additive lengths of said pair of links being less than the distance between their points of attachment to said frame, a pulley mounted in fixed position adjacent the other end of said arm, means for removably suspending a boat from said arm in the inboard position thereof, and a fall running over said pulley and attached to said removable suspension means.

4. A gravity type davit unit for launching a boat from the deck of a ship, comprising a rigid frame mounted on such ship; a pair of pivot pins mounted in parallel relationship on said frame; a davit arm for carrying a boat; a second pair of pivot pins mounted in parallel relationship at one end of said davit arm; the distance between the pivot pins mounted on said arm being no greater than the distance between the pivot pins mounted on said frame; the length of said davit arm being no less than the distance between the pivot pins mounted on said frame; a link rotatably mounted at one end to one of the pivot pins on said frame and rotatably mounted at the other end to one of the pivot pins on said arm; a second link rotatably mounted at one end to the other pivot pin on said frame and rotatably mounted at the other end to the other pivot pin on said arm; the additive lengths of said two links being less than the distance between the pivot pins mounted on said frame; pulley means mounted adjacent the other end of said arm; means for suspending a boat from said arm in the inboard position thereof; and a fall running over said pulley means and attached to said suspension means; the relative lengths and dispositions of said links and said arm, and the distances between said pivot pins being characterized by the fact that the vertical through the center of rotation of said pulley means always passes to the outboard side of the instantaneous point of intersection of the longitudinal axes of said links.

5. A gravity type davit unit for launching a boat from the deck of a ship, comprising a frame mounted on such ship; a plurality of pivot pins mounted in parallel relationship on said frame; a plurality of links; each of said pins having one of said links rotatably mounted upon it adjacent one end of said link; a davit arm for carrying a boat; a plurality of pivot pins mounted in parallel relationship adjacent one end of said arm; each of said pivot pins mounted on said arm having the other end of one of said links rotatably mounted upon it; and means for suspending a boat from said davit arm in the inboard position thereof, the relative motions of said arm and said links being characterized by the fact that in the extreme inboard and extreme outboard positions of said arm the pivot pins

5 10 15 20 25 30 35 40 45 50 55 60 65

mounted on said arm are on opposite sides of the line joining the centers of the pivot pins mounted on said frame.

6. A gravity type davit unit for launching a boat from the deck of a ship, comprising a frame mounted on such ship; a plurality of pivot pins mounted in parallel relationship on said frame; a plurality of links; each of said pins having one of said links rotatably mounted upon it adjacent one end of said link; a davit arm for carrying a boat; a plurality of pivot pins mounted in parallel relationship adjacent one end of said arm; each of said pivot pins mounted on said arm having the other end of one of said links rotatably mounted upon it; said links constituting the only means of connection between said frame and said arm; and means for suspending a boat from said davit arm in the inboard position thereof, the relative motions of said arm and said links being characterized by the fact that in the extreme inboard and extreme outboard positions of said arm the pivot pins mounted on said arm are on opposite sides of the line joining the centers of the pivot pins mounted on said frame.

7. A gravity type davit including a pair of davit units, each unit comprising a frame for mounting on a ship, a pair of pivot pins mounted in parallel relationship on said frame, a pair of links, each rotatably mounted on one of said pins, a davit arm of greater length than either of said links, means pivotally securing said davit arm at one end to said links with its boat suspending end at all times outboard of the instantaneous point of intersection of the longitudinal axes of said links, and means for removably suspending a boat from said arms in the inboard position thereof.

8. A gravity type davit including a pair of davit units, each unit comprising a frame for mounting on a ship, a pair of pivot pins mounted in parallel relationship on said frame, a pair of links, each rotatably mounted on one of said pins, said pair of pivot pins constituting the only means of supporting said links on said frame, a davit arm of greater length than either of said links, means pivotally securing said davit arm at one end to said links, with its boat suspending end at all times outboard of the instantaneous point of intersection of the longitudinal axes of said links, said pair of links constituting the only means of support for said arm on said frame, and the additive lengths of said links being less than the distance between their points of attachment to said frame, and means for removably suspending a boat from said arms in the inboard position thereof.
